BABY'S NIPPLE TONGS

Prosper R. Knapp, Los Angeles, Calif.

Application December 1, 1938, Serial No. 243,445

6 Claims. (Cl. 81—5.1)

This invention relates to a tool especially adapted for applying nursing nipples to babies' bottles and also may be employed for removing nipples and bottles from a sterilizing bath.

5 An object of this invention is the provision of a device of the above stated character which is simple and convenient to operate with one hand and which will permit a person to apply a nipple to a bottle without touching the nipple with the hands, thereby obviating any possibility of contaminating the nipple and is of such a construction that the base of the nipple may be spread and held in a stretched position to permit easy and quick placing thereof on the bottle and to be 15 released on said bottle in a properly applied position.

With these and other objects in view the invention consists in certain novel features of construction, combination and arrangement of parts 20 to be hereinafter more fully described and claimed.

For a complete understanding of my invention, reference is to be had to the following description and accompanying drawings, in which

25 Figure 1 is a perspective view illustrating a tool constructed in accordance with my invention and showing the application thereof to a nipple prior to spreading and holding the nipple stretched.

Figure 2 is a top plan view illustrating the tool.

30 Figure 3 is a top plan view illustrating the tool spreading and holding stretched a nipple, the latter being diagrammatically illustrated.

Figure 4 is a fragmentary end elevation illustrating a portion of a baby's bottle and the tool positioned thereover with the nipple both shown 35 unstretched and stretched ready for application onto the bottle.

Referring in detail to the drawings, the numeral 5 indicates elongated handles pivotally connected, as shown at 6. The handles where pivotally connected are abruptly curved and brought into overlapping relation. Integral with the handles and forming a continuation of the pivoted ends thereof are arcuately curved jaws 7, the end portions of which are bent at right angles thereto to form upstanding extensions 8 each having notches 9 and 10. The notches 9 are opposed to each other and are arranged in a plane below the notches 10 and the latter-named notches are arranged on opposite sides of the extensions from the notches 9, as will be clearly apparent in Figure 4.

The jaws 7 and their extensions are employed for spreading and holding the base portion of a nipple 11 spread. Coacting with the jaws 7 for

spreading the base of the nipple is a spring member 12 substantially V-shaped having its ends fastened onto the jaws 7 adjacent the pivot 6, while the bight portion thereof is bent angularly to form an extension 13 normally arranged adjacent the extensions 8. The spring member 12 acts normally to urge the jaws 7 toward each other with the handles in a spread position, as shown in Figure 2. The extensions 8 and 13 are placed within the base of the nipple and by moving the 10 handles toward each other the base portion of the nipple is spread and held stretched, as shown in Figure 3.

Coacting with the extensions 8 to retain the base of the nipple thereon when the latter is 15 spread or stretched, as shown in Figure 3, are retaining arms 14 arranged in crossed relation and each has a hook-shaped end 15 and the opposite end angularly disposed, as shown at 16, and fastened onto a jaw 7. By referring to Figure 2 20 it will be seen that when the ends 16 of retaining arms 14 are applied to the jaws 7, the arms cross each other and also cross over the jaw to which they are not applied or secured. The tendency of the retaining arms 14 is to spread apart, that is, 25 the hook-shaped ends when the jaws 7 are moved in the direction of each other. However, when the jaws 7 are moved away from each other the arms 14 or hook-shaped ends thereof move toward the extensions 8 and come in contact with the 30 exterior walls of the base of the nipple and thereby obviate any possibility of the nipple slipping off of the extensions 8 and 13. The hook-shaped ends 15 will force the walls of the base of the nipple into the notches 10 of the extensions 8, as 35 shown in Figure 4, thereby effectively securing the nipple onto the tool in a spread and stretched position. Further, it will be seen that the extension 13 moves away from the extensions 8 as the jaws 7 are moved apart, consequently, the base 40 of the nipple is supported or held as shown diagrammatically in Figure 3, whence it may be readily slipped over the mouth of a bottle 17 and when so positioned the tool may be easily released therefrom by simply allowing the handles 5 to 45 move apart under the action of the spring member 12 contracting the jaws 7 and spreading the retaining arms 14 and allowing the extension 13 to move toward the extensions 8. Then by tipping the handles upwardly which tends to move the 50 extensions 13 and 8 downwardly or at an angle they may be readily withdrawn from the base of the nipple allowing the latter to contract onto the neck of the bottle.

Therefore, it will be seen that a very efficient 55

and practical tool has been provided whereby a nipple may be spread and held stretched to permit its application to a bottle without the hands coming in contact therewith, consequently preventing the nipple from being contaminated and provides a very efficient and quick means of applying a nipple in a sanitary way.

While this invention has been described as especially adaptable for applying a nipple onto a bottle it may also be employed for lifting nipples, as well as bottles, from a sterilizing bath. To remove a bottle from a sterilizing bath, the extensions 8 are placed inside of the neck of the bottle and the handles are squeezed together causing the extensions 8 to coact with the hook-shaped ends 15 of the arms 14 to coact in tightly gripping the neck of the bottle so it can be lifted from the sterilizing bath without the hands coming in contact therewith. Nipples are removed from the sterilizing bath in a like manner with the invention.

In use there are two types of bottles and nipples, one type bottle having a comparatively large open mouth and the nipple therefor is constructed with a comparatively large base while the other type of bottle has a small neck and the nipple therefor has a comparatively small base to match the small neck. The present invention will handle either type of bottle and nipple. In applying a small size nipple to a small size neck of a bottle, the hook-shaped ends 15 of the arms need not be employed. However, on the application of a large size nipple to a large size bottle it is essential that the hook-shaped ends of the arms be employed.

During the application of the nipple by this tool onto the neck of a bottle with the jaws 7 in a spread position, the flange of the bottle may enter the notches 9 at diametrically opposite sides of the bottle and on the release of the handles 5 to move apart and the jaws 7 to move toward each other the extensions 8 ride about the flange toward each other obviating any possibility of the extensions becoming disengaged from the flange during the application of the nipple onto the bottle.

It is believed that the simplicity and advantages of this invention will be perfectly apparent to those skilled in the art to which such a device relates, and while I have herein set forth a satisfactory embodiment of my invention, it is to be understood that such changes therefrom as fairly fall within the scope of my claims may be resorted to when desired.

What I claim is:

1. A tool of the character described comprising pivotally connected handles, arcuately curved jaws formed on said handles and having their free ends angularly disposed to provide extensions, spring means connected to the jaws between said extensions and the pivot of the handles and acting on said jaws for normally urging the jaws toward each other and having an extension located adjacent to and coacting with the first-named extensions in engaging in a base of a nipple for spreading and holding the base of the nipple stretched by movement of the jaws away from each other.

2. A tool of the character described comprising a pair of handles pivotally connected at one end, arcuately curved jaws formed on the pivoted ends of the handles and including nipple-

engaging means, and spring means connected with said jaws adjacent the pivot of the handles and acting to urge the jaws toward each other and to provide means located adjacent to and coacting with the first-named means in engaging a nipple.

3. In a tool of the character described comprising pivotally connected handles, arcuately curved jaws formed on said handles, extensions formed on said jaws and arranged at right angles thereto, a spring member including ends connected to the jaws adjacent to the pivots of the handles and acting to urge the jaws toward each other and having a portion thereof bent at right angles to form an extension located adjacent to and coacting with the first-named extensions in engaging and spreading and holding a base of a nipple in a stretched position.

4. In a tool of the character described comprising pivotally connected handles, arcuately curved jaws formed on said handles, extensions formed on said jaws and arranged at right angles thereto, a spring member having ends thereof secured to the jaws adjacent the pivot of the handles and acting to urge the jaws toward each other and having a portion thereof bent at right angles to form an extension located adjacent to and coacting with the first-named extension in engaging and spreading and holding a base of a nipple in a stretched position, said first-named extension having notches, and means carried by said jaws to engage the base of the nipple for forcing the latter into the notches on the spreading of said nipple by the jaws.

5. In a tool of the character described comprising pivotally connected handles, arcuately curved jaws formed on said handles, extensions formed on said jaws and arranged at right angles thereto and provided with notches, a spring member connecting said jaws and tending to urge the jaws toward each other and having a portion thereof bent at right angles to form an extension located adjacent to and coacting with the first-named extensions in engaging and spreading and holding a base of a nipple in a stretched position, crossed retaining arms mounted on said jaws and having hook-shaped ends to engage with the nipple on being stretched for forcing portions of said nipple into the notches.

6. In a tool of the character described comprising pivotally connected handles, arcuately curved jaws formed on said handles, extensions formed on said jaws and arranged at right angles thereto and provided with notches, a spring member connecting said jaws adjacent the pivot of the handle and tending to urge said jaws toward each other and having a portion thereof bent at right angles to form an extension located adjacent to and coacting with the first-named extensions and engaging and spreading and holding a base of a nipple in a stretched position, crossed retaining arms mounted on said jaws and having hook-shaped ends to engage with the nipple on being stretched for forcing portions of said nipple into the notches, said first-named extensions having notches to engage with a flange of a bottle neck on the application of the nipple onto the neck.
